UNITED STATES PATENT OFFICE.

CONRAD HOERL, OF NEWARK, NEW JERSEY.

ROTARY COMPRESSOR.

1,291,520.

Specification of Letters Patent. Patented Jan. 14, 1919.

Application filed December 6, 1917. Serial No. 205,832.

To all whom it may concern:

Be it known that I, CONRAD HOERL, a citizen of the United States, residing at Newark, in the county of Essex and State of New Jersey, have invented certain new and useful Improvements in Rotary Compressors; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention has reference, generally, to improvements in fluid compressors and the like; and the invention relates, more particularly, to a novel improved construction of rotary air or other fluid compressor.

20 The invention has for its principal object to provide a simple, easily operated and efficient construction of rotary air compressor provided within its interior with a novel arrangement and construction of rotated oscillating compressor vanes or leaves, and a novel means for driving or operating the latter.

25 The invention has for a further object to provide, in connection with the novel rotary compressor mechanism, a novel means and arrangement of lubrication for the internal moving parts of the compressor.

Other objects of the present invention, not at this time more particularly enumerated, 30 will be clearly understood from the following detailed description of the same.

With the various objects of my present invention in view, the same consists, primarily, in the novel construction of air compressor 35 hereinafter set forth; and, the invention consists, furthermore, in the various novel arrangements and combinations of the several devices and parts, as well as in the details of the construction of the same, all of which will be more fully described in the 40 following specification, and then finally embodied in the appended claims.

The invention is clearly illustrated in the accompanying drawings, in which:—

50 Figure 1 is a top or plan view of the novel air compressor made according to and embodying the principles of my present in-

vention; Fig. 2 is an elevation of one end of the same, and Fig. 3 is an elevation of the opposite end of the same; Fig. 4 is a transverse section through the novel air compressor, taken on line 4—4 in said Fig. 1, looking in the direction of the arrow *x*; Fig. 5 is a longitudinal cross section through the novel compressor, taken on line 5—5 in said Fig. 4, looking in the direction of the arrow *y*; Fig. 6 is a detail longitudinal cross section of the same, taken on line 6—6 in said Fig. 4, looking in the direction of the arrow *z*; and Fig. 7 is a detail side elevation of the coupling devices interconnecting the driving pulley with the driving shaft of the compressor.

Similar characters of reference are employed in all of the hereinabove described views, to indicate corresponding parts.

Referring now to the said drawings, the reference character 1 indicates a cylindrical casing within which the rotary compressor mechanism is mounted. Said casing is provided at one side with an intake port 2, and at its opposite side with a discharge port 3. Said ports are respectively formed to pass through outwardly projecting portions 4 and 5, preferably forming an integral part 75 of the cylindrical casing 1, and provided at their outer extremities with perforate ears 6, to which may be bolted the flanges 7 of suitable coupling devices or unions 8, from which extend respectively, an air supply 9 and an air discharge pipe 10, whenever it is desirable to use either the one or the other or both of the latter.

One end of said cylindrical casing 1 is closed by means of an end plate 11, secured by bolts, or otherwise, to said casing 1. Securely fixed to said end plate 11, so as to extend longitudinally through the interior of said casing 1, and so disposed as to be positioned eccentrically relative to the 90 inner circumference of said casing 1, is a cylindrical core-member 12, the same being hollow so as to provide a reservoir chamber 13. The inner face of said end plate 11 is provided with an outer annular concentric seat or guideway 14, one side of which (the outer side) is formed by the inner surface of the wall of the casing 1, and the inner face of said end plate 11 is further

provided with an inner annular eccentric seat or guideway 15, one side of which (the inner side) is formed by the outer surface of the wall of said core-member 12. Securely fixed to the inner free end of said core-member 12 is a guide-plate G, the outer circumference of which is concentric to the inner circumference of the casing 1, and spaced therefrom 5 to provide an outer annular concentric guideway 16, axially or longitudinally opposite said concentric seat or guideway 14. Said guide-plate G is further provided, on its inner side, with an inner annular eccentric seat or guideway 17, one side of which (the inner side) is formed by the outer surface of the wall of said core-member 12, said seat or guideway 17 being axially or longitudinally opposite said seat or guideway 15. 10 Seated respectively in said outer annular concentric guideways 14 and 16, are rotatable ring-members 18, and extending longitudinally between said ring-members 18, and interconnecting the same, are a plurality of pintle rods 19, the same being spaced equidistant one from the other about the said ring-members 18. Journaled respectively upon said pintle rods 19, by means of their outer bearing portions 20 are a series of compressor vanes or leaves 21, the said outer bearing portions 20 thereof being so disposed as to contact slidably, in all positions thereof during the oscillatory movements of said compressor vanes or leaves, with the inner surface of said casing 1. The inner ends of said compressor vanes or leaves 21 are curved inwardly, as at 22, to so shape the vanes or leaves as to render their oscillatory movements relative to the 15 walls of the casing 1 most effective during the air compressing action or movement thereof, and at the same time assuring a proper clearance of the core-member 12 thereby during said oscillatory movements. 20 Disposed within said respective seats or guideways 15 and 17, so as to ride slidably around therein, are a plurality of shoes 23. Extending longitudinally between opposite shoes 23, and interconnecting the same are 25 a plurality of pintle rods 24, upon which the inner bearing portions 25 of said compressor vanes or leaves are pivotally connected. 30 The said ring members 18 and the said shoes 23 are disposed flush with the respective inner surfaces of said end plate 11 and the guide-plate 16, and the side edges 26 of said compressor vanes or leaves 21 ride slidably in contact with said flush surfaces, so that there is practically no leakage therebetween during the compressing movements 35 of said vanes or leaves 21.

The reference character 27 indicates packing strips, preferably made of a suitable metal, such for example as brass or bronze.

These packing strips are each provided on their under sides with a concave surface 28 conforming to the cylindrical surface of said core-member 12, and on their upper sides with a concave surface 29 conforming to the cylindrical surface of the inner bearing portions 25 of said compressor vanes or leaves. When assembling the compressor vanes or leaves in place, one of said packing strips is inserted between each bearing portion 25 thereof and the core-member 12, and owing to the oppositely curved conformation of the said parts between which the same is located, it follows that said strips are interlocked therewith, and as thus arranged will move with the inner ends of the vanes or leaves 80 upon the surface of the core-member, thus closing any intervening space against the leakage of air when the vanes or leaves are oscillated to compress the air on one side thereof. 85

The opposite end of said cylindrical casing 1 is closed by means of an end plate 30, secured by bolts, or otherwise, to said casing 1. Said end plate 30 is provided with a centrally disposed outwardly extending bearing portion 31, having an extension 32 of reduced diameter at its outer end. Mounted in said bearing portion 31 is a driving shaft 33, to the inner end of which is secured, by means of a key 34, or otherwise, a driver disk 35. Said driver disk 35 is equal in diameter to the diameter of the interior of the cylindrical casing 1, and the same is provided at its outer circumferential edge with an inwardly projecting annular flange 36, 100 preferably disposed to ride in a portion of said outer concentric guideway 16, and in engagement with the ring member 18 mounted therein. Said ring member 18 is connected in driven relation to said driver disk 105 35 by means of studs or pins 37, which project from said flange 36 into openings 38 formed in said ring member 18 for their reception. The said driving shaft 33 projects outwardly through said bearing portion 31. 110 One means for driving said shaft 33 comprises a pulley 39, which is mounted upon said reduced extension 32 to rotate thereon. The hub 40 of said pulley projects outwardly beyond the end of said extension 32, 115 and is provided with a pair of diametrically opposite female clutch portions 41. Secured in fixed relation to the outwardly projecting end of said shaft 33, by means of set-screws 42, or other suitable means, is a clutch-collar 43, provided with a pair of diametrically opposite male clutch portions 44 engaged in said female clutch-portions 41 of said pulley hub 40. When said pulley 39 is driven by a belt, the rotary motion imparted thereto is transmitted through the above described clutch elements to the shaft 33. Since, however, the pulley is mounted to ro-

tate on the extension 32, any pulling strains thereon tending to distort an exact path of rotation is prevented from being exerted upon the shaft 33, and consequently the latter is driven smoothly on its axis by means of the intermediate clutch elements, thereby eliminating any tendency to undue friction or binding of the rotated interior mechanism and compressor vanes and leaves of the device within the cylindrical casing 1. While I find the above means for driving the shaft 33 very satisfactory when the compressor is belt driven, I do not wish to be necessarily confined to such method of driving as far as the broader aspects of my invention are concerned, since it will be quite apparent that my novel compressor may be driven direct by electric motor, or it may be driven by gearing or any other suitable transmission means, either directly or indirectly from any desired source of power.

In operation, the rotation of the shaft 33 rotates the driver disk 35 connected therewith, imparting in turn a rotary movement to the ring members 18. Since the compressor vanes or leaves 21 are pivotally connected by their outer ends to said ring members 18, said outer ends of said vanes or leaves 21 are moved around in a path of travel concentric to the axis of rotation. The inner ends of said vanes or leaves 21, while the latter are thus caused to revolve about the axis of rotation, being supported by the shoes 23 riding in the guideways 15 and 17 which are disposed eccentric to the axis of rotation, are caused to travel in a path eccentric to the axis of rotation, so that as the path of eccentricity of the inner ends of the vanes or leaves approaches the concentric path of the outer ends of the vanes or leaves, the latter are caused to oscillate bodily toward the wall of the cylindrical casing 1, and thereby effect a compressing action upon any fluid confined between the vanes or leaves and said wall of the casing 1, while as the path of eccentricity of the inner ends of the vanes or leaves departs from the concentric path of the outer ends of the vanes or leaves, the latter are caused to oscillate bodily in a reverse direction or away from the walls of the casing 1, thereby effecting a suction like action to suck or draw into the opening space between the said vanes or leaves and walls of the casing any desired fluid from a source of supply. The intake port 2 of the casing 1 is so located as to deliver the fluid within the cylinder at a point where the said above described suction oscillation of the vanes or leaves is effective, and the outlet or discharge port 3 of the casing 1 is so located as to discharge the fluid from the cylinder under the compression produced by the said above described compressing oscillation of the vanes

or leaves. Since a series of rotating oscillated vanes or leaves are employed, the suction and compressing action thereof is successively developed as the same are rotated within the casing 1, and consequently a substantially continuous discharge of fluid 70 under compression through the discharge port 3 is effected. As will be apparent the action is simple yet effective, and dependent upon the oscillation of the rotated vanes or leaves, due to the travel of the opposite ends 75 thereof respectively around the concentric and eccentric paths of travel, the degree of eccentricity of the latter relative to the former determining the oscillatory stroke, and being subject to such variation as may 80 seem desirable, and properly proportioned to the size and capacity of apparatus desired.

In addition to the novel construction and operation of the compressor above described, 85 I wish to point out another novel feature of the construction thereof, whereby an efficient lubrication of the interior moving parts thereof is secured. This means of lubrication comprises providing the end 90 plate 11 with a chambered boss or projection 45, either integrally formed therewith or suitably secured thereto. The interior 46 of said chambered boss or projection 45 communicates with an opening 47 leading into 95 the reservoir chamber 13 formed by the interior of said core member 12. Connected with said boss 45, so as to communicate with the interior 46 thereof, is an oil supply pipe 48, which leads from a suitable source of oil supply. The oil fed through said supply pipe 48 enters said interior 46 of said boss 45, and flows into said reservoir chamber 13 of said core member 12. Formed in the wall at each end of said core member 12 is 100 an opening or duct 49 in which is arranged a piece of wicking 50, the inner end of which is submerged in the oil 51 contained in said reservoir 13. The said opening or duct 49 communicates with each eccentric guideway 110 15 and 17, so that the wicking can convey the oil thereto, to be taken up by the shoes 23 traveling in said guideways, thereby lubricating the same, and reducing the friction of their movement in said guideways. Any 115 surplus of oil thus carried into said guideways 15 and 17 works its way into the pivotal connection of the inner ends of said vanes or leaves 21 with the pintle rods 24, and also flows through additional openings 120 or ducts 52 affording a path of communication between said guideways 15 and 17 with said guideways 14 and 16, so that surplus oil may also enter the latter to lubricate the same and thereby reduce the friction of the ring members 18 traveling therein, said oil also working its way into the pivotal connection of the outer ends of said vanes or

leaves 21 with the pintle rods 19, thus effectively lubricating against undue friction all the moving parts within the interior of the casing 1, and rendering the operation of the compressor smooth and easy.

I am aware that some changes may be made in the general arrangements and combinations of the devices and parts, as well as in the details of the construction of the same, without departing from the scope of my present invention as defined in the appended claims. Hence, I do not limit my invention to the exact arrangements and combinations of the various devices and parts as set forth in the foregoing specification, nor do I confine myself to the exact details of the construction of said parts as illustrated in the accompanying drawings.

I claim:—

- 20 1. In a device of the kind described, a cylindrical casing, a plurality of compressor vanes mounted within said casing for rotation about the axis of said casing, means for moving the outer ends of said vanes in a rotary path concentric to the axis of said casing, means for causing the inner ends of said vanes to move in a rotary path eccentric to the axis of said casing, whereby said vanes are caused to oscillate toward and away from the cylindrical wall of said casing while so rotated about the axis of the latter, the outer ends of said vanes coöperating slidingly with the cylindrical wall of said casing, an eccentrically disposed core member within said casing with which the inner ends of said vanes slidingly coöperate, and said casing being provided with an intake port on one side and a discharge port on the opposite side.
- 40 2. In a device of the kind described, a cylindrical casing, a plurality of substantially radially disposed compressor vanes mounted within said casing for rotation about the axis of the latter, the outer ends of said vanes coöperating slidingly with the cylindrical wall of said casing, an eccentrically positioned longitudinally disposed core member within said casing with which the inner ends of said vanes slidingly coöperate, means for rotating said vanes about the axis of said casing, means engaging the inner ends of said vanes to guide the same in an eccentric path of movement about the axis of said casing to cause the same to oscillate toward and away from the cylindrical wall of said casing during rotative travel therein, and said casing having an intake port positioned to communicate with the space between said vanes when the same oscillate away from the cylindrical wall of said casing and a discharge port positioned to communicate with the space between said vanes when the same oscillate toward the cylindrical wall of said casing.

3. In a device of the kind described, a cylindrical casing, an end plate closing one end of said casing, an eccentrically positioned longitudinally disposed core member extending inwardly through said casing from said end-plate, a guide-plate secured to the inner end of said core-member, said end plate and said guide-plate being formed to provide in conjunction with said cylindrical wall of said casing oppositely located outer guideways concentric to the axis of said casing and in conjunction with said core member oppositely located inner guideways eccentric to the axis of said casing, a plurality of substantially radially disposed compressor vanes mounted between said end plate and said guide plate, means riding in said outer concentric guideways for pivotally supporting the outer ends of said compressor vanes, and rotating the latter about the axis of said casing, means riding in said inner eccentric guideways for pivotally supporting the inner ends of said compressor vanes and guiding the same in an eccentric path of movement about the axis of said casing whereby the same are caused to oscillate toward and away from the cylindrical wall of said casing, the outer ends of said vanes coöperating slidingly with the cylindrical wall of said casing, the inner ends of said vanes coöperating slidingly with said core member, and said casing having an intake port in its cylindrical wall adapted to communicate with the space between said vanes when the same oscillate away from the wall of said casing and a discharge port positioned in its cylindrical wall adapted to communicate with the space between said vanes when the same oscillate toward the wall of said casing.

4. In a device of the kind described, a cylindrical casing, an end plate closing one end of said casing, an eccentrically positioned longitudinally disposed core member secured to said end-plate within said casing, a guide-plate secured to the free end of said core-member, said end-plate and said guide-plate being formed to provide in conjunction with said cylindrical wall of said casing oppositely located outer guideways concentric to the axis of said casing and in conjunction with said core member oppositely located inner guideways eccentric to the axis of said casing, ring-members rotatably mounted in said outer concentric guideways, shoe-pieces mounted to move slidingly in said inner eccentric guideways, a plurality of substantially radially disposed compressor vanes mounted between said end plate and said guide plate, means for pivotally connecting the outer ends of said vanes with and between said ring members, means for pivotally connecting the inner ends of said vanes with and between

- pairs of said shoe-pieces, the outer ends of said vanes coöperating slidingly with the cylindrical walls of said casing, the inner ends of said vanes coöperating with said 5 core member, means connected with the opposite end of said casing providing a centrally or axially disposed bearing portion, a shaft journaled in said bearing portion, a rotary driver disk secured to the inner end 10 of said shaft, means coupling said driver disk with an adjacent ring member to impart rotary movement to said vanes, and said cylindrical wall of said casing having on one side an intake port and on its opposite side a discharge port. 15
5. In a device of the kind described, a cylindrical casing, an end plate closing one end of said casing, an eccentrically positioned longitudinally disposed core member secured to said end-plate within said casing, a guide-plate secured to the free end of said core member, said end plate and said guide-plate being formed to provide in conjunction with said cylindrical wall of said casing 20 oppositely located outer guideways concentric to the axis of said casing and in conjunction with said core member oppositely located inner guideways eccentric to the axis of said casing, ring-members rotatably 25 mounted in said outer concentric guideways, shoe-pieces mounted to move slidingly in said inner eccentric guideways, a plurality of substantially radially disposed compressor vanes mounted between said end 30 plate and said guide plate, means for pivotally connecting the outer ends of said vanes with and between said ring members, means for pivotally connecting the inner ends of said vanes with and between pairs 35 of said shoe-pieces, the outer ends of said vanes coöperating slidingly with the cylindrical walls of said casing, the inner ends of said vanes coöperating with said core member, packing strips 40 engaged between said inner ends of said vanes and the surface of said core member in slidable relation to the latter, means for driving said ring-members to rotate said vanes, and said cylindrical wall 45 of said casing having on one side an intake port and on its opposite side a discharge port. 50
6. In a device of the kind described, a cylindrical casing, an end plate closing one end of said casing, an eccentrically positioned longitudinally disposed core member secured to said end-plate within said casing, a guide-plate secured to the free end of said core-member, said end plate and said guide-plate being formed to provide in conjunction with said cylindrical wall of said casing 55 oppositely located outer guideways concentric to the axis of said casing and in conjunction with said core member oppositely located inner guideways eccentric to the axis of said casing, ring-members rotatably mounted in said outer concentric guideways, shoe-pieces mounted to move slidingly in said inner eccentric guideways, a plurality of substantially radially disposed compressor vanes mounted between said end 60 plate and said guide-plate, means for pivotally connecting the outer ends of said vanes with and between said ring members, means for pivotally connecting the inner ends of said vanes with and between pairs of said shoe-pieces, the outer ends of said vanes coöperating slidingly with the cylindrical 65 walls of said casing, the inner ends of said vanes coöperating with said core member, packing strips engaged between said inner ends of said vanes and the surface of said core member in slidable relation to the latter, means connected with the opposite end of said casing providing a centrally or axially disposed bearing portion, a shaft jour- 70 75 80 85 90 95 100 105 110 115 120 125
- located inner guideways eccentric to the axis of said casing, ring-members rotatably mounted in said outer concentric guideways, shoe-pieces mounted to move slidingly in said inner eccentric guideways, a plurality of substantially radially disposed compressor vanes mounted between said end plate and said guide plate, means for pivotally connecting the outer ends of said vanes with and between said ring members, means for pivotally connecting the inner ends of said vanes with and between pairs of said shoe-pieces, the outer ends of said vanes coöperating slidingly with the cylindrical walls of said casing, the inner ends of said vanes coöperating with said core-member, packing strips engaged between said inner ends of said vanes and the surface of said core member in slidable relation to the latter, means connected with the opposite end of said casing providing a centrally or axially disposed bearing portion, a shaft jour-

naled in said bearing portion, a rotary driver disk secured to the inner end of said shaft, means coupling said driver disk with an adjacent ring member to impart rotary movement to said vanes, a pulley mounted to rotate on said bearing portion, the hub of said pulley having female clutch portions at one end thereof, a clutch collar secured to the outer end of said shaft having male clutch portions engaged in said female clutch portions of said pulley hub, and said cylindrical walls of said casing having on one side an intake port and on the opposite side a discharge port.

8. In a device of the kind described, a cylindrical casing closed at its ends by end plates, an eccentrically positioned core member connected with one end plate to extend longitudinally through said casing, a guide-plate connected with the inner free end of said core member, an annular frame-work mounted to rotate within said casing in a path concentric to the axis of the latter, concentric guide-means provided by said end plate and said guide-plate for said frame-work, a plurality of substantially radially disposed compressor vanes pivoted by their outer ends to said frame-work between said end plate and said guide-plate, eccentric guide means provided by said end plate and said guide-plate, shoe-pieces slidably supported by said eccentric guide means to which the inner ends of said vanes are pivoted, packing-strips between the inner ends of said vanes and said core member, the outer ends of said vanes slidably cooperating with the cylindrical wall of said casing, a transmission means rotatably connected with the opposite end plate for driving said frame-work, and said cylindrical wall of said casing having on one side an intake port and on its opposite side a discharge port.

9. In a device of the kind described, a cylindrical casing closed at its ends by end plates, an eccentrically positioned core member connected with one end plate to extend longitudinally through said casing, a guide-plate connected with the inner free end of said core member, an annular frame-work mounted to rotate within said casing in a path concentric to the axis of the latter, concentric guide-means provided by said end plate and said guide-plate for said frame-work, a plurality of substantially radially disposed compressor vanes pivoted by their outer ends to said frame-work between said end plate and said guide-plate, eccentric guide means provided by said end plate and said guide-plate, shoe-pieces slidably supported by said eccentric guide means to which the inner ends of said vanes are pivoted, packing-strips between the inner ends of said vanes and said core-member, the outer ends of said vanes slidably cooperating with the cylindrical wall of said casing, a bearing portion connected with the opposite end plate, a shaft mounted in said bearing portion, a driver-disk connected with the inner end of said shaft, means for coupling said driver disk with said frame-work, a journal-like extension connected with said portion, a pulley mounted to rotate on said extension, a female clutch means connected with said pulley, a clutch collar fixed on the outer end of said shaft, male clutch means on said collar engaged operatively with the female clutch means of said pulley, and said cylindrical wall of said casing having on one side an intake port and on its opposite side a discharge port.

10. In a device of the kind described, a cylindrical casing closed at its ends by end plates, an eccentrically positioned core member connected with one end plate to extend longitudinally through said casing, a guide-plate connected with the inner free end of said core member, an annular frame-work mounted to rotate within said casing in a path concentric to the axis of the latter, concentric guide-means provided by said end plate and said guide-plate, shoe-pieces slidably supported by said eccentric guide means to which the inner ends of said vanes are pivoted, packing-strips between the inner ends of said vanes and said core-member, the outer ends of said vanes slidably cooperating with the cylindrical wall of said casing, a bearing portion connected with the opposite end plate, a shaft mounted in said bearing portion, a driver-disk connected with the inner end of said shaft, means for coupling said driver disk with said frame-work, a journal-like extension connected with said portion, a pulley mounted to rotate on said extension, a female clutch means connected with said pulley, a clutch collar fixed on the outer end of said shaft, male clutch means on said collar engaged operatively with the female clutch means of said pulley, and said cylindrical wall of said casing having on one side an intake port and on its opposite side a discharge port.

outer ends of said vanes slidably co-operating with the cylindrical wall of said casing, a bearing portion connected with the opposite end plate, a shaft mounted in said bearing portion, a driver-disk connected with the inner end of said shaft, means for coupling said driver disk with said frame-work, means for rotating said shaft, and said cylindrical wall of said casing having on one side an intake port and on its opposite side a discharge port.

11. In a device of the kind described, a cylindrical casing closed at its ends by end plates, an eccentrically positioned core member connected with one end plate to extend longitudinally through said casing, a guide-plate connected with the inner free end of said core member, an annular frame-work mounted to rotate within said casing in a path concentric to the axis of the latter, concentric guide-means provided by said end plate and said guide-plate, shoe-pieces slidably supported by said eccentric guide means to which the inner ends of said vanes are pivoted, packing-strips between the inner ends of said vanes and said core-member, the outer ends of said vanes slidably cooperating with the cylindrical wall of said casing, a bearing portion connected with the opposite end plate, a shaft mounted in said bearing portion, a driver-disk connected with the inner end of said shaft, means for coupling said driver disk with said frame-work, a journal-like extension connected with said portion, a pulley mounted to rotate on said extension, a female clutch means connected with said pulley, a clutch collar fixed on the outer end of said shaft, male clutch means on said collar engaged operatively with the female clutch means of said pulley, and said cylindrical wall of said casing having on one side an intake port and on its opposite side a discharge port.

12. In a device of the kind described, a cylindrical casing, an end plate closing one end of said casing, an eccentrically positioned chambered core-member fixed to said end plate to extend into said casing, the interior of said core-member providing a reservoir, a guide-plate fixed to the inner end of said core-member, concentric outer guideways provided by portions of said guide-plates and said end plate, eccentric inner guideways provided by other portions of said guide-plate and said end-plate, a plurality of substantially radially disposed compressor vanes arranged between said

guide-plate and said end plate, rotary means mounted in said concentric guideways to which the outer ends of said vanes are pivoted, sliding shoes mounted in said eccentric guideways to which the inner ends of said vanes are pivoted, an end-plate connected with the opposite end of said casing, means associated with said opposite end plate for driving said rotary means, said cylindrical wall of said casing having an intake port on one side and a discharge port on the opposite side, means for delivering lubricating substance into said reservoir formed by said chambered core-member, the walls of said core-member having ducts for delivering said lubricating substance into said eccentric guideways, and said end plate and said guide-plate having additional communicating ducts between said eccentric guideways and said concentric guideways.

12. In a device of the kind described, a cylindrical casing, an end plate closing one end of said casing, an eccentrically positioned chambered core-member fixed to said end-plate to extend into said casing, the interior of said core-member providing a reservoir, a guide-plate fixed to the inner end of said core-member, concentric outer guide-ways provided by portions of said guide-plate and said end plate, eccentric inner guideways provided by other portions of said guide-plate and said end-plate, a plurality of substantially radially disposed compressor vanes arranged between said guide-plate and said end-plate, rotary means mounted in said concentric guideways to which the outer ends of said vanes are pivoted, sliding shoes mounted in said eccentric guideways to which the inner ends of said vanes are pivoted, an end plate connected with the opposite end of said casing, means associated with said opposite end plate for driving said rotary means, said cylindrical wall of said casing having an intake port on one side and a discharge port on the opposite side, means for delivering lubricating substance into said reservoir formed by said chambered core-member, the walls of said core-member having ducts for delivering said lubricating substance into said eccentric guideways, and means for conveying said lubricating substance from said reservoir to the interior moving parts of the mechanism.

13. In a device of the kind described, a cylindrical casing having an intake port on one side and a discharge port on the opposite side thereof, an end plate closing one end of said casing, an eccentrically positioned core-member fixed to said end plate to extend into said casing, a guide-plate fixed to the inner end of said core-member, concentric outer guideways provided by portions of said guide-plate and said end plate, eccentric inner guideways provided by other

portions of said guideplate and said end 65
plate, a plurality of substantially radially
disposed compressor vanes arranged between
said guide-plate and said end-plate, a rotary
means mounted in said concentric guideways
to which the outer ends of said vanes are 70
pivoted, sliding shoes mounted in said ec-
centric guideways to which the inner ends
of said vanes are pivoted, an end plate con-
nected with the opposite end of said casing,
and means associated with said opposite end 75
plate for driving said rotary means.

14. In a device of the kind described, a cylindrical casing having an intake port on one side and a discharge port on the opposite side thereof, an end plate closing one end of said casing, an eccentrically positioned core-member fixed to said end plate to extend into said casing, a guide-plate fixed to the inner end of said core-member, concentric outer guideways provided by portions of said guide plate and said end plate, eccentric inner guideways provided by other portions of said guide plate and said end-plate, a plurality of substantially radially disposed compressor vanes arranged between said guide plate and said end plate, a rotary means mounted in said concentric guideways to which the outer ends of said vanes are pivoted, sliding shoes mounted in said eccentric guideways to which the inner ends of said vanes are pivoted, an end plate connected with the opposite end of said casing, means associated with said opposite end plate for driving said rotary means, comprising a bearing portion connected with said opposite end-plate, a shaft mounted in said bearing portion and a driver disk fixed on the inner end of said shaft to which said rotary means is coupled.

15. In a device of the kind described, a cylindrical casing having an intake port on one side and a discharge port on the opposite side thereof, an end plate closing one end of said casing, an eccentrically positioned core-members fixed to said end plate to extend into said casing, a guide-plate fixed to the inner end of said core-member, concentric outer guideways provided by portions of said guide-plate and said end-plate, eccentric inner guideways provided by other portions of said guide-plate and said end-plate, a plurality of substantially radially disposed compressor vanes arranged between said guide-plate and said end-plate, a rotary means mounted in said concentric guideways to which the outer ends of said vanes are pivoted, sliding shoes mounted in said eccentric guideways to which the inner ends of said vanes are pivoted, an end plate connected with the opposite end of said casing, means associated with said opposite end-plate for driving said rotary means, comprising a bearing portion connected with said opposite 105 110 115 120 125

end-plate, a shaft mounted in said bearing portion, a driver disk fixed on the inner end of said shaft to which said rotary means is coupled, a journal-like extension connected with said bearing portion, a pulley mounted to rotate on said extension, a female clutch means connected with said pulley, a clutch collar fixed on the outer end of said shaft, and female clutch means on said collar en-

gaged operatively with the female clutch 10 means of said pulley.

In testimony, that I claim the invention set forth above I have hereunto set my hand this 4th day of December, 1917.

CONRAD HOERL.
